COMBINED ADJUSTABLE STRAIGHT-EDGE,
RULE, AND ALIGNMENT TESTER

Daniel H. Wieslander, Portland, Maine

Application July 2, 1936, Serial No. 88,565

8 Claims. (Cl. 164—73)

This invention relates, in general terms, to improvements in combination rules and straight-edges, dealing more particularly with that type of device used by paper hangers for trimming wall paper to a straight line.

Straight-edges are made usually of wood, with metal edges in the form of channels, although in some instances the complete implement is constructed of metal. In the present instance, however, I have elected to illustrate and describe my invention as fabricated from wood and metal.

In the conventional type of straight-edge made of the two materials mentioned the wood will, after a time, start to warp and bend, causing the metal cutting edge to be distorted and out of truth. And as ordinarily constructed it is a somewhat difficult matter to again put the straight-edge into proper workable shape.

The present invention has been conceived with the object in view of incorporating within the body of the straight-edge certain structure whereby any informality in alignment of the cutting edge may be easily and quickly corrected and the device brought back to its original shape and condition for cutting true, straight lines.

Briefly, the invention consists in a plurality of adjusting screws operated from the back edge of the straight-edge and engaging the cutting edge channel on the opposite or front side of the device at separated points along its length, each screw acting to draw or repel the particular part of the channel to which it is attached into alignment with a central portion which may be fixed to the body portion of the straight-edge.

The invention further contemplates means for checking the accuracy of the alignment as the screws are being actuated.

In order to better understand the import of my invention reference should be had to the description found in the following specification when taken in connection with the accompanying drawing disclosing an embodiment which, at the present time, I consider preferable to other possible forms in which the invention might be carried out.

In the drawing, in which like reference characters are employed to identify similar parts in all the different views,—

Fig. 1 is a perspective view of my straight-edge device;

Fig. 2 is a transverse section taken on line 2—2, Fig. 1;

Fig. 3 is a transverse section taken on line 3—3, Fig. 1;

Fig. 4 is a sectional plan view of the straight-edge, the section being taken on line 4—4, Fig. 3;

Fig. 5 is a fragmentary, enlarged view of Fig. 3; Fig. 6 shows a fragmentary view in perspective, of the adjustable cutting edge channel;

Fig. 7 is a detail having to do with the taut-line testing elements used in checking the alignment of the cutting edge channel;

Fig. 8 is a view of the cutting edge side of the straight-edge with a conventional type trimmer shown mounted thereon;

Fig. 9 illustrates a slightly modified form of track over which the trimmer moves in cutting the paper, and

Fig. 10 shows an alternative method of securing the internally threaded studs to the channel, and

Fig. 11 is an enlarged sectional view of a part of Fig. 4.

Referring to the drawing, 1 is the body portion of my straight-edge, preferably although not necessarily made of wood. On its top surface is an ordinary scale 2 graduated in inches and fractions of an inch. The device may be made of any desired length, but as shown, it represents one of seventy-two inches in length.

On its left hand side, as when viewing it in Fig. 2, the straight-edge is protected and somewhat stiffened by a channel member 3, the same being secured to the wood body by screws 4.

On the opposite, or right-hand side of the device is a transversely adjustable channel member 5, the outer faces of the two legs of which, as also applies in the case of channel 3, being preferably flush with the top and bottom surfaces, respectively, of the straight-edge. If preferred, the lower legs of both channels may extend below the bottom face of the wood body, the transversely intervening portion of the straight-edge then being out of contact with the paper being trimmed.

It will be observed that the web portion 5a, constituting the cutting edge of channel 5, is spaced from the edge 1a of the wooden body, a distance x. This permits flexing of the channel either toward or from the adjacent edge 1a of the straight-edge.

While I do not restrict myself to the following construction, I may elect to anchor the longitudinally central portion of the channel 5 to the body of the straight-edge. In this case I insert in the space x a short shim 6 and draw the central portion of the web 5a strongly thereonto. Adjustments transversely of the straight-edge may now be made on the channel 5 on portions thereof lying lengthwise on either side of the central portion. By removal of the shim 6 all

parts are susceptible of flexing, transversely of the straight-edge.

At intervals along the length of the straight-edge, on each side of the section to which the channel 5 is fixedly attached, are holes 8, (see Fig. 5), within which are disposed, respectively, the bolts 9. The slotted heads 9a of these bolts operate in counterbores 10, and their outer faces thrust on the inside of the channel 3. Placed ahead of the bolt head 9a, in each case, is a washer 11 and a spring washer 12, the function of the latter being to maintain the bolt head in constant engagement with the wall of the channel 3.

15 A hole 13 is made in the channel 3, abreast and in alignment with each of the bolt-heads 9a in order to provide access to the slot 9b in the bolt-head with a screw-driver.

Secured to and disposed on the inside face of 20 the wall 5a of the channel 5 are a plurality of internally screw-threaded studs 14, in each of which one of the bolts 9 has screw-threaded engagement.

The top leg 5b of the channel 5 overhangs a 25 longitudinal groove 15 made in the wood body of the straight-edge, forming a lip which prevents vertical displacement of the paper trimmer T from the straight-edge during paper trimming operations. Fig. 8 illustrates a conventional type 30 trimmer, the angular member A operating in the slot or groove 15, and engaging the under side of the overhanging portion of the leg 5b of the channel, the roll R travelling over the top surface of the channel and the cutter C travelling 35 along the channel side 5a while trimming the paper. The trimmer device forms no part of the present invention and is shown simply to bring out the purpose or object of the straight-edge in wall-paper-trimming work.

40 The leg 5b of the channel 5 (see Fig. 5) constitutes a rail upon which the roll R travels as it moves along the straight-edge. In other words, it supports the trimmer body on which the cutter C is swingingly mounted.

45 In service, and after long continuous work, it is found that considerable "play" develops between the parts so that the trimmer becomes more or less unstable.

In Fig. 9 I illustrate a slightly modified form 50 of rail upon which the trimmer traverses the straight-edge. The slot 15, in Fig. 5 design, is slightly enlarged, as at 15a, and a supplementary rail 16 set into the top of the wood portion 1 of the straight-edge, leaving a short lip or overhanging portion 16a. The trimmer, in this instance, has a T form of rail-engaging member 55 Aa, which contacts the under side of each of the rail elements, 5b and 16, and has two rolls, Ra. This construction provides a much wider base 60 for supporting the trimmer in action.

On each end of the straight-edge is pivotally 65 secured a thin plate 17, having near its free end a tapering incision 17a. In Fig. 7 this plate is shown in its housed position in full lines. Upon 70 swinging it outwardly, as shown in dot and dash lines, after first loosening the pivot screw 18, and then tightening this screw, a wire or fine cord 19 may be stretched from one to the other of the plates, the line or wire being locked in the tapering cut out portion 17a by drawing it downwardly until it binds in the crotch of the incision.

75 After the cord is tightly drawn and secured in the plates 17, as seen in Fig. 4, it serves as means by which the accuracy, or inaccuracy, of

the cutting edge of the straight-edge may be checked, by using inside calipers.

With the shim 6 in place, the bolt 9 located at M, midway the length of the straight-edge, is rotated, drawing the threaded stud 14 inwardly. 5 This acts to bind the shim and channel portion 5a firmly against the body edge 1a.

In Fig. 5 the member 14 is shown shouldered, with the reduced portion riveted to the web of the channel. Fig. 10 illustrates another method 10 of attaching the internally threaded studs to the channel, namely, by spot welding, the stud having a flange on its end to give a larger area or surface presented to the face of the channel for support. 15

In making the alignment test by the caliper method, the distance between the tautened cord 19 and the face of the cutting-edge 5a abreast of the shim 6 is calibrated, and this distance taken as a base measurement. If any portions 20 or locations along the length of the cutting-edge deviate from this base measurement the respective bolts 9 are actuated, or rotated either one way or the other, to bring all parts or portions of the cutting-edge into longitudinal alignment relatively, and into parallelism with the cord 19. 25

It may develop that the straight-edge is substantially true and straight, but the paper-hanger cannot safely assume this until after he has made the test. 30

In some instances, as when the wooden portion is abnormally bent or crooked, it may be desirable to dispense with the shim 6, in which case all the bolts 9 are actuated to bring the cutting-edge true. 35

I have, hereinbefore, stated that it is optional as to the material used in the body portion of my straight-edge, although I preferably employ wood for this member.

Anything made of wood is likely to shrink 40 more or less after being made into a finished article or commodity. Shrinkage end-wise, however, is very much less than cross-wise the grain, but I have deemed it wise to take cognizance of the fact that my straight-edge will shrink longitudinally to a certain extent. 45

Were the bolts 9 all made to snugly fit the holes 8, the shrinkage of the wood might cause a strain on the members 14, resulting in their being detached from the channel 5, or else cause 50 them to be distorted at the immediate point of attachment to the channel web. This would be due, of course, to the fact that the wood shrinks and the metal channel does not, resulting in disaligning the holes in the body 1 and channel 55 web 5a.

In Fig. 11, showing a portion of Fig. 4 on an enlarged scale, the longitudinally central bolt 9 (shown in Fig. 4 at C) makes a tight fit in the hole 8, so that to all intents and purposes the 60 channel is anchored to the wooden body of the straight-edge at this location.

From this central position, toward each end of the straight-edge, the holes 8 progressively increase in size to permit freedom of movement 65 of the wood as it shrinks and swells, so that there is no conflict or alignment difficulties occasioned by change of center to center measurements of the holes 8 should the body portion of the straight-edge change its form. 70

Provision is also made with respect to the securing means for the channel 3 which is attached to the body 1 by screws 4. The countersunk holes 4a, which receive the heads of the flat-head screws 4, is slightly elongated, allowing for a 75

certain amount of "play" between the screw-head and the web of the channel 3.

With a straight-edge capable of being maintained in correct form with respect to the straightness of its cutting-edge, a paper-hanger works with full assurance that when he makes a cut in the trimming of the wall-paper it will be straight and true.

He can, therefore, work to better advantage than he otherwise could. He saves time in correcting faults in trimming over the workman who is using an out-of-true straight-edge; and he very often eliminates the waste of paper which due to the character of the pattern or design of the figure thereon cannot be re-cut to advantage.

While I have described the invention as it applies to the art of trimming wall-paper, it is not to be understood that I limit myself to this particular application, in practice, as it is obvious that it will be found very useful and of advantage in other situations where the object is to delineate a true, straight line.

What I claim is:

1. An adjustable straight-edge and rule comprising in combination a wooden body element having on one of its faces a slot extending the full length thereof, a metal channel-shape member disposed over one edge of said wooden body element and fixedly secured thereto, a second metal channel member, having one side wall constituting a cutting edge, disposed over but spaced from the opposite edge of said wooden body member, a short shim disposed between said cutting edge and the adjacent edge of said wooden body element, and means to flex, transversely of the straight-edge, the portions of said second metal channel member disposed, longitudinally, on either side of said shim.

2. An adjustable straight-edge comprising in combination a wooden central member, a channel element fixedly secured on one edge of said member, said element having a plurality of holes therein, and extending for the full length of said member, a second channel element, constituting a cutting edge for said straight-edge, disposed on the opposite edge of said central member, and spaced from said edge, a plurality of internally threaded studs secured in the cutting edge wall of said second channel member, said studs being arranged in spaced order for the full length of said second channel member, and a plurality of bolts, having slotted heads, passing through said central member, the said heads thrusting on the inside face of the first channel member, and the opposite ends of said bolts having screw-threaded engagement, respectively, with the said internally screw-threaded studs.

3. An adjustable straight-edge and alignment tester comprising in combination a body portion having a longitudinal slot along its upper face, a channel fixedly secured to and encompassing one edge of said body portion, a second channel encompassing the opposite edge of said body portion, its central, or web portion constituting the cutting-edge of said straight-edge, one leg of said second channel overhanging the slot in the body portion, means to flex said second channel in a direction normal to the body edge which it encompasses, at a plurality of points along its length, a plate pivotally secured on each end of said body portion, and an open-end tapering incision made in one side of said plate, whereby when said plates are swung from their housed positions on the end of said body portion outwardly, said incisions are disposed beyond the

outer face of said cutting-edge and are adapted to receive a cord which when tautened serves as means for checking the accuracy, with respect to straightness, of said cutting-edge.

4. A device of the class described adapted for use in wall paper trimming operations comprising in combination a wooden rule having a longitudinally extending groove on one of its faces and a plurality of longitudinally spaced bolt-receiving holes bored transversely of said rule, a channel member fixedly secured on one edge of said rule, the web portion thereof having holes aligning, respectively, with said bolt-receiving holes, a second channel member disposed on the opposite edge of said rule, its web portion, constituting the cutting edge for the device, being spaced from the adjacent edge of the rule, a plurality of internally threaded studs secured to and on the inside face of the web of said second channel member, the studs aligning, respectively, with the bolt-receiving holes in said rule, a bolt, having a slotted head abutting on said first channel member, disposed in each of the said bolt-receiving openings, with its threaded end engaging one of said studs, whereby upon rotating said bolt said cutting-edge is flexed, and a plate having a V-shape notch cut in its side secured pivotally at each end of said rule, and when swung outwardly adapted to receive and secure in said notches a tautened cord into parallelism with which all portions throughout the length of said cutting-edge are adapted to be brought, successively, by rotation of the respective bolts.

5. An adjustable straight-edge and rule comprising a body member, a groove cut on the upper face of said body member, extending for the full length thereof, a channel member enclosing one edge of said body portion for its entire length, and means incorporated in said body portion for flexing said channel member at various locations along its length, transversely of said body portion, for the purpose of bringing all points of the channel, lengthwise of the straight-edge, into mutual alignment.

6. A straight-edge adapted for use in trimming wall paper comprising in combination a body member having a longitudinal groove in its top face and a plurality of longitudinally spaced bolt-receiving holes extending transversely from edge to edge of said member, the ends of said holes being counterbored, a channel member, constituting a cutting-edge for said straight-edge, mounted over the front edge of said straight-edge, the web of said channel member being, normally, spaced from the edge of the body member and its two legs adapted, respectively, to slidably engage the top and bottom faces of the body member, the upper of the two said legs overhanging said groove in the body member, a plurality of slotted-head bolts operating, respectively, in the said holes in the body member, the heads of the bolts being disposed in the respective counterbores on the back edge of the body member, and their opposite ends having screw-threaded engagement with said cutting-edge channel member, a second channel member, having a plurality of holes in its web portion smaller than the heads of said bolts and aligning therewith, fixedly secured to and enclosing the back edge of said body member, and a spring washer on each of said bolts, disposed inwardly of its head, adapted to thrust on the bottom of said counterbore and the inner face of the bolt head, to hold said bolt in strong, yielding contact with

the web of the second mentioned channel member.

7. An adjustable straight-edge comprising in combination a wooden body portion, a channel element secured to and enclosing one edge of said body portion, said channel element having a plurality of slotted screw-apertures therein, a second channel element enclosing the whole length of the opposite edge of said body portion, the web 10 of the last mentioned channel element being, normally, disposed in spaced relation to the adjacent edge of the body portion, adjusting members incorporated in said body portion engaging, respectively, said second mentioned channel element at a plurality of locations disposed at intervals throughout its length, said members adapted to maintain, respectively, the said plurality of locations on the channel member last mentioned in mutual, longitudinal alignment after first being brought thereinto, and means in said

straight-edge to permit endwise shrinkage of said body portion without re-positioning or disaligning said adjusting members.

8. An adjustable straight-edge and rule comprising a body portion having a groove on its top face extending for the full length of the straight-edge, a channel member enclosing one edge, and transversely slidably on adjacent portions of the top and bottom faces, of said body portion, the upper leg of said channel member overhanging 10 said groove, and a rail secured to and on the top face of said body portion, aligning horizontally with the top leg of said channel member and overhanging the opposite side of said groove, said rail together with the top leg of said channel member constituting means for supporting and guiding a paper-trimming device during paper-cutting operations. 15

DANIEL H. WIESLANDER. 20
